STANCHION LOCKING MECHANISM

John B. Olson, Fort Atkinson, Wis., assignor
to James Manufacturing Company, Fort
Atkinson, Wis., a corporation of Wisconsin

Application April 24, 1930. Serial No. 446,823

4 Claim. (Cl. 119—147)

My invention relates to improvements in stanchion locking mechanism.

The primary object of my invention is to provide means for adjusting and locking a stanchion from a point sufficiently distant from the animal to avoid danger of personal injury, said mechanism being so constructed as to allow it to be adjusted and locked within the smallest possible time interval.

10 Further objects are to provide a stanchion locking mechanism which cannot be released by the animal, which can be at all times adjusted to either the locking or the unlocking position, and the associated stanchion opened or closed, 15 by a simple movement of a lever in two directions; also to provide durable and inexpensive stanchion operating and locking mechanism which can be employed to swing either or both of the stanchion bars to closed or open position, 20 and in which ample leverage may be obtained for moving the bar or bars against pressure such as the animal may be exerting upon it and which might otherwise prevent the desired movement.

25 In the drawing:

Figure 1 is an exterior isometric view of a portion of the corner of a pen for cattle, equipped with my invention.

Figure 2 is a plan view of the same.

30 Figure 3 is a view of the locking plates and associated parts, in the position which they occupy when the stanchion is closed.

Figure 4 is an elevational view of the parts shown in Fig. 3 as seen from the left hand side 35 in Fig. 2, the upper frame bar being shown in section taken to line 4—4 of Fig. 2.

Figure 5 is a section taken to line 5—5 of Fig. 4.

Like parts are identified by the same reference characters throughout the several views.

40 In Fig. 1 the stanchion comprises a pair of bars 10 and 11 having their lower ends pivoted at 12 to clamping brackets 13 engaged with the lower bar 14 of a pen frame. The upper ends of 45 the bars 10 and 11 are loosely engaged with the upper bar 15 of the pen frame, preferably by means of forked heads 16.

In the construction shown, the bars 14 and 15 are arcuate due to the fact that the stanchion is 50 associated with a corner manger (not shown) commonly employed for individual pens for cattle.

The particular structure of the pen and of the stanchion is not material to the invention herein claimed, and further illustration or descrip-

tion thereof is deemed unnecessary, except to point out that the sliding heads 16 at the upper ends of the stanchion bars 10 and 11 are provided with a plurality of bolt apertures 18 to facilitate coupling the adjusting mechanism thereto as hereinafter explained.

At a point remote from the stanchion a metal bearing plate 20 is secured to the stanchion frame. It may be attached to an upper bar 21 of the pen frame, which bar, in the construction shown, is an upper frame bar of the pen at one side of the corner in which the illustrated stanchion is located. I preferably provide this bar 21 with a bracket 22 clamped to rod 21 and having a raised central portion 23 upon which the plate 20 may be mounted and connected by a bolt 25, the plate 20 being upwardly offset in the portion that fits over the raised center 23 of the bracket 22, whereby the plate 20 may be interlocked with the bracket to prevent it from rotating and to relieve the bolt 25 from undue strain.

The upwardly offset portion 26 of the bracket 20 serves as a platform or bearing upon which an oscillatory stanchion adjusting plate 27 is 80 mounted and held by the bolt 25 and a nut 28, which serves to retain the plate 27 in position while allowing it to oscillate upon the bolt in turn-table relation to the bearing plate 20.

The fixed bearing plate 20 is provided with a 85 pair of notches 30 and 31.

The oscillatory plate 27 is forked at one end and provided with upturned flanges 29 to which an operating lever 33 is pivoted by means of a cross bolt or pin 34. This lever 33 is adapted to 90 swing into and out of either of the notches 30 and 31 when in registry therewith, and when in engagement with one of the notches it occupies a vertical position of suspension from its pivotal connection 34. It will be obvious that by swinging the lever 33 to a horizontal position it will be released from the relatively fixed plate 20, and it may then be used to oscillate plate 27 about the axis of the pivot bolt 25.

The respective ends of the plate 27 are attached to the stanchion bars 10 and 11 by connecting rods 36 and 37. The connecting rods have double knuckle joint connection with the stanchion head 16, the couplings 38 having an upwardly extending pivot bolt 39 and a horizontal pivot bolt 40, the latter extending through one of the holes 18 in the stanchion head.

At their opposite ends the connecting rods are pivoted to vertically extending bolts 42 carried by the plate 27. It will therefore be obvious that

by oscillating the plate 27 from the position in which it is shown in Fig. 1, to the position in which it is shown in Fig. 3, the stanchion bars 10 and 11 may be actuated in opposite directions and caused to approach each other to the dotted line position indicated in Fig. 1, which is the animal retaining position.

It will be observed that the rod 36 is pivoted to one of the fork arms of the plate 27. By providing an aperture 45 in the other fork arm, the plate is made reversible so that it can be used at either the right or the left hand side of the stanchion. When used at the right hand side, the connecting rod 36 will have its pivot bolt 42 inserted through the aperture 45.

It will of course be understood that the operating lever 33 will normally be held by gravity in the locking position. Pressure exerted by the animal upon the stanchion bars will of course be transmitted to the plate 27, but no excessive strain will be exerted upon the pivotal connection of the lever for the reason that the lever substantially fits the space between the flanges 29, and the notches 30 and 31 are of substantially the same width as the diameter of the lever with proper clearance to allow the lever to swing freely into and out of the notches. The two plates being in contact with each other, the lever itself will resist any tendency of one plate to oscillate upon the other, without material strain upon the pivot pin.

It will of course be understood that where only one stanchion bar is to be swung into and out of animal retaining position, only one connecting rod will be required, and this may be connected at either end of the oscillatory plate 27 to suit the requirement of the installation. Ordinarily a longer movement will be required if but one stanchion bar is adjusted to retain or release the animal. The length of movement will of course depend upon the distance between the axis about which plate 27 oscillates and the point at which the connecting rod is secured thereto. Therefore, the length of the plate will depend upon the degree of the desired movement of the associated stanchion bar or bars.

The field of movement of each stanchion bar is determined by the location of the bolt 40, and where both bars are to be swung, the degree of their separation and approach may be varied by shifting the bolts 40 from one hole 18 to another.

The plate 27 constitutes a double acting crank having a foldable actuating arm which, when folded for engagement in either of the notches 30 or 31, operates as a latch or locking member.

I claim:

1. The combination with a pen frame having upper and lower arcuate frame bars, of a plurality of stanchion bars pivoted to said lower frame bar, stanchion adjusting mechanism, including a notched catch plate fixed with said upper frame bar, a crank plate mounted thereon and centrally pivoted thereto, stanchion adjusting linkage pivoted to the respective end portions of the crank plate and operatively connected to upper portions of said stanchion bars, and an operating arm pivoted to the crank plate at right angles to its axis and adapted to interlock with the catch plate in a plurality of positions of crank plate adjustment.

2. The combination with a pen frame having arcuate upper and lower frame bars, a set of stanchion bars pivoted to the lower frame bar and having their upper ends slidably engaged with the upper frame bar, and laterally distant support mounted on the pen frame and provided with a bearing surface, a crank plate centrally pivoted for oscillation on said bearing surface and having portions on opposite sides of said pivotal connection linked respectively to the stanchion bars, and a latch arm pivoted to said crank plate for swinging movement in a plane perpendicular thereto, said arm and bearing plate being adapted for interlocking engagement when the arm is in one position of swinging adjustment.

3. In a stanchion adjusting mechanism, a rotative crank plate having a radially extending slot flanked by upset flanges, and an operating arm pivotally connected with said flanges and adapted for swinging movement into and out of said slot, said crank plate being adapted for connection with stanchion adjusting linkage on opposite sides of the slot and near the margin of the plate on the opposite side of its axis of rotation from that occupied by the slot.

4. The combination with the upper frame bar of a stanchion frame, of a bracket having its ends connected therewith and its intermediate portion upwardly offset, a bearing plate formed to interlock with the upwardly offset portion of the bracket and provided with a notched margin, a crank plate in turn-table relation to the bearing plate, said crank plate, bearing plate and bracket being connected together by a pivot bolt, and an operating arm pivoted to the crank plate and adapted by downward movement to engage with a registering notch in the bearing plate, said crank plate being adapted for connection with stanchion adjusting linkage at a plurality of points.

JOHN B. OLSON.
